Paul D. Phillips
By Jones, Addington, Amer. Leibig

UNITED STATES PATENT OFFICE

PAUL D. PHILLIPS, OF CHICAGO, ILLINOIS, ASSIGNOR TO BENJAMIN ELECTRIC MANUFACTURING COMPANY, OF CHICAGO, ILLINOIS, A CORPORATION OF ILLINOIS

WIRING TERMINAL CONSTRUCTION

Application filed September 8, 1928. Serial No. 304,650.

My invention relates to wiring terminal construction.

One of the objects of my invention is to provide an improved construction in which the wiring may be effected by inserting the bared ends of the wires into openings in the receptacle base and thereafter operating a swivel screw to cause the end of the wire to be gripped.

10 A further object is to provide an improved construction in which the head of the swivel screw is accessible for operation through the shell contact.

A further object is to provide a construction in which the base has openings for stocking the slack in case there is no room to push the slack back into the conduit or housing.

15 A further object is to provide an improved construction in which the socket interior may be secured in the shell in various adjusted positions.

Further objects will appear from the description and claims.

In the drawings, in which an embodiment 25 of my invention is shown,

Fig. 1 is a side elevational view of a receptacle construction, parts being broken away;

Fig. 2 is a bottom view of the socket interior;

Fig. 3 is an axial section of the socket interior;

Fig. 4 is a top plan view of the socket interior; and

35 Fig. 5 is a perspective view of the wiring terminal construction.

Referring to the drawings in detail, the construction shown therein comprises threaded shell and center contact members, 1 and 2, 40 a pair of wiring terminal constructions 3 and 4 for these contacts respectively and an insulating base 5 on which said contacts and wiring terminals are mounted.

The wiring terminal construction shown 45 in perspective in Fig. 5 comprises a sheet metal stamping 6 having upper and lower bearing portions 7 and 8 and an intermediate inclined backing portion 9 extending between and connecting the bearing portions, 50 a screw 10 swiveled in the bearing openings

in said spaced bearing portions and a nut 11 threaded on said screw having a beveled edge 12 between which and the inclined backing portion the bared end 13 of the wire is clamped. The screw is held in assembled 55 relation with respect to the stamping by pinching the end of the screw, as shown at 14, after the screw has been passed through the bearing openings. The head 15 of the screw serves to hold the receptacle contact 60 in assembled relation with respect to the wiring terminal, the shank of the screw passing through an opening in the securing portion 16 of the receptacle contact.

The center and shell contacts are held in 65 place on the insulating base by means of an insulating button or disc 17 of suitable sheet material between which and the insulating base the securing portions 16 of the contacts are clamped. The disc is positioned by means 70 of an elongated boss 18 (Fig. 2) on the insulating base, which fits in a corresponding shaped hole in the disc. The disc is secured on the insulating base by means of a pair of eyelets 19.

75 The insulating base is provided with suitable openings 20 extending longitudinally of the axis thereof for receiving and guiding the bared ends 13 of the wires into proper engagement with the wiring terminals.

In order to provide storage space for any slack in the wires which cannot be pushed back into the conduit or housing the sides of the insulating base are provided with recesses or pockets 21 to receive a loop 22 of the wire, 80 passages 23 being provided in the upper side of the insulating base leading from the longitudinally extending openings 20 to the side recesses 21 respectively.

85 The receptacle interior is housed in a sheet metal shell 24 which also serves to cover the side recesses 21 and top passages 23. The upper end of the sheet metal shell is secured to a hexagonal nut 25 having a hexagonal portion 26 lying inside of the shell and engaging a correspondingly spaced hexagon-shaped recess 27 in the upper face of the insulating base. By means of this engagement the 90 socket interior may be secured and positioned 95 100

in the shell in various positions of angular adjustment.

In order to hold the socket interior in the shell 24 a screw ring 28 is provided, the upper edge of which engages a shoulder 29 on the insulating base 5, the ring having a threaded engagement with the lower threaded portion 30 of the shell.

In assembling the device, a subassembly is made up including the center contact and its wiring terminal construction, another subassembly is made up including the threaded shell contact and its wiring terminal construction, the two subassemblies with the insulating disc or button 17 are then put in place on an assembly jig and the insulating base 5 is then slipped over the assembly jig, the parts assembled thereon and the entire construction is secured together by riveting 20 the eyelets 19 which have also been put in position on the assembly jig.

In wiring the receptacle all that is necessary to do is to operate the swivel screws 10 until the nuts 11 are at the upper limit of 25 their movement, bare the ends of the wires for about half an inch, insert these bared ends into the openings 20 as far as they will go, and then operate the swivel screws to draw the clamping nuts downwardly to pinch the 30 ends of the wires against the inclined backing portions.

While I have shown but one embodiment of my invention, it is obvious that it may be embodied in other forms covered and defined 35 by the appended claims.

I claim:

1. A wiring terminal construction comprising a swivel screw held against endwise movement, a member having a pair of spaced bearing portions in which said screw is swiveled 40 and an intermediate inclined backing portion, and a nut between said bearing portions engaged and moved axially by said screw, between which nut and the backing portion 45 the wire is held.

2. A wiring terminal construction comprising a swivel screw held against endwise movement, a member having a pair of spaced bearing portions in which said screw is swiveled 50 and an intermediate inclined backing portion, and a nut between said bearing portions engaged and moved axially by said screw, between which nut and the backing portion the wire is held, said screw having a head for 55 engagement by a screw driver and an enlarged portion engaging one of said bearing portions to hold the screw against endwise movement.

In witness whereof, I have hereunto sub-
scribed my name.

PAUL D. PHILLIPS.
